UNITED STATES PATENT OFFICE.

RICHARD S. GIESE, OF SEWICKLEY HEIGHTS TOWNSHIP, ALLEGHENY COUNTY, PENNSYLVANIA.

DESIGN FOR A GLASS GOBLET.

Application filed December 17, 1927. Serial No. 24,514. Term of patent 3½ years.

To all whom it may concern:

Be it known that I, RICHARD S. GIESE, a citizen of the United States, residing in Sewickley Heights Township, in the county of Allegheny and State of Pennsylvania, have invented a new, original, and ornamental Design for Glass Goblets, of which the following is a specification, reference being had to the accompanying drawing, forming part thereof.

The figure is a view in perspective of a glass goblet, showing my new design. At its margin the foot of the goblet is encircled with an opaque and lustrous band of metal. At its upper rim, both inside and outside, the goblet is bordered with opaque metal bands.

I claim:

The ornamental design of a glass goblet, as shown and described.

RICHARD S. GIESE.
